CONTROL OF COMBUSTION IN IN SITU TREATMENTS OF CARBONACEOUS DEPOSITS

Walter C. Sheldon, Englewood, Colo., assignor to Marathon Oil Company, a corporation of Ohio

Filed Dec. 26, 1961, Ser. No. 162,211

10 Claims. (Cl. 166—11)

This invention relates to a treatment of underground reservoirs and more particularly relates to methods of preparing underground carbonaceous deposits for subsequent in situ combustion recovery treatments.

In situ combustion techniques for recovery of petroleum values from carbonaceous deposits are well known in the art. They are frequently used for secondary recovery treatment of oil reservoirs when such reservoirs can no longer be economically worked by conventional pumping methods. Such methods also are used for initial treatment of other types of petroleum deposits when the viscosity of the material in a reservoir is too high for economical pumping operations. Such deposits may include tar sands and other reservoirs containing viscous petroleum liquids.

These latter deposits frequently occur in relatively thick formations. For purposes of this invention a relatively thick formation may be defined as one that exceeds thirty feet in thickness. When treating such relatively thick formations or deposits by in situ combustion operations, the upper portion of the deposit tends to burn or burns much more rapidly than its lower portions. This apparently is the result of differences in density between the injected air and the hydrocarbons (oil) in place which causes a propagated flame front to spread upwardly and outwardly, while downward movement is retarded; and undesirable overburning of limited areas of the reservoir above the point of initial flame propagation occurs, resulting in loss of valuable petroleum material which otherwise might have been recovered.

It is an object of this invention to provide a simple, efficient and economical method of treating relatively thick underground reservoirs in order to condition or prepare them for controlled in situ combustion recovery operations.

It is another object of the invention to provide a simple, efficient and economical method of preparatory treatment for a lower portion of combustion zones in a carbonaceous deposit for providing balanced or controlled in situ combustion throughout the upper and lower portions thereof.

It is still another object of the invention to provide a simple, economical and efficient method of controlling the direction and rate of advance of the combustion front in in situ combustion operations performed in relatively thick petroleum reservoirs.

When using the method of controlling in situ combustion in carbonaceous deposits according to this invention, for formation to be treated is penetrated by a plurality of wells, and in the usual practice these wells will include an injection well and one or more production wells. The production wells may be located in any of the conventional or other spacing pattern employed in recovery of crude oil by other secondary methods. One such pattern is the "inverted five-spot" pattern in which a substantially centrally located injection well has four production wells spaced at substantially even intervals thereabout.

2

As shown in the accompanying drawing, the injection well 1 and a plurality of production wells 2a and 2b should be drilled downward through substantially the entire depth of the formation 3 to be treated. A packer 4 is set in injection well 1 to separate the deposit 3 into two parts. Preferably, packer 4 is located in relation to the permeability of the structure and in some instances two packers may be used at vertically spaced points in the well.

Casing 5 may be placed in injection well 1 to any depth, and casing 6a and 6b preferably are provided for wells 2a and 2b, respectively. Preferably the casings are capped at the surface, and support one or a plurality of conduits. Conduits 7 and 7a are supported in casing 5 to deliver fluid (solution or air) to selected depths in injection well 1 and conduit 8a in casing 6a and conduit 8b in casing 6b deliver the production material to the surface. In preparing for operation, an aqueous solution of a suitable combustion catalyst or an oil soluble catalyst is injected through the injection well 20 below the packer or packers and introduced into the lower zones or portions of the deposit to be treated. A catalyst is employed to serve one or both of two functions, i.e., to promote or control combustion and/or initiate combustion by spontaneous combustion. The catalyst 25 is introduced through the well as a solution so as to distribute it through the portions of the formation where combustion is to be controlled. After combustion is initiated, the combustion front movement is controlled by the relative distribution of air or other oxygen-containing gas.

In one procedure utilizing my invention, the catalyst system is comprised of an aqueous solution of a suitable metal salt which is initially injected into the deposit through the injection well below the packer, and between 35 packers if a plurality of packers is used, and thence into the surrounding formation. The pyrophoric material is then formed in place from the injected solution by suitable treatment, such as the introduction of hydrogen sulfide to form a pyrophoric metallic sulfide when a pyrophoric 40 material is desired. Under some circumstances, a pyrophoric material will not be desired, in which case an aqueous solution of a suitable catalyst such as a metallic salt is injected without further treatment. Thereafter, air is injected into the treated area. If pyrophoric material has been utilized, spontaneous combustion results 45 from the air introduction. Where a non-pyrophoric catalyst is employed, conventional ignition practices will be required.

As an example of utilizing a pyrophoric material, an 50 through an injection well, followed by the injection of a quantity of hydrogen sulfide gas or hydrogen sulfide in natural gas. The $FeCl_2$ and the hydrogen sulfide react to form FeS and hydrogen chloride. When this reaction is essentially complete, a quantity of dry air is injected, 55 which causes spontaneous ignition of the FeS and thus propagation of a combustion front in the lower portion of the deposit. The quantity of hydrogen sulfide which is injected is preferably in a stoichiometric excess of that required for complete reaction of the iron chloride, or 60 in excess of that required to completely react the $FeCl_2$ solution above described.

The air injection is an important factor of the foregoing method of initiating the combustion front action. Since the catalyst used is initially in an aqueous solution, 65 the air flow must be continued until such time as it is substantially dry in order for it to spontaneously ignite.

Once combustion has been initiated the quantity of air injected is determined by desired temperatures and rates of flame front movement. Further, by use of suitable temperature sensitive probes or thermocouples, together with quantitative control of the air or oxygen enriched gas which is injected into the combustion zone, it is possible to closely control the temperature of the flame front, as well as its rate of movement.

In some deposits, it may be desirable to initiate or control a combustion front at more than one level. In such a deposit, an internal casing is inserted within the outer well casing, thereby providing a pair of concentric flow paths to the formation to be treated. Otherwise, multiple strings of tubing may be used. By use of suitable packers and selective perforation of the outer casing, it is possible to initiate a flame front at any of a plurality of levels. In such an arrangement, the catalytic material in an aqueous solution is passed downwardly through the appropriate passage to the desired portions of the formation. Next, hydrogen sulfide or hydrogen sulfide in natural gas, if such is required, is passed downwardly through the same passage as the catalyst. Subsequently, air or other oxygen enriched gas is passed down through the flow paths in quantities appropriate to maintain temperature and/or rate of frontal advance.

In either of the foregoing described procedures, it is sometimes desirable to leave the packer or packers in place since it yields a greater degree of control over the operation relative to the rates of air injection to the flame front. From the foregoing, it will be apparent that at least some permeability is required in the deposit in which the in situ combustion operation is to be conducted after preparation for treatment according to this invention. It is to be understood that in less permeable formations, when necessary, sand fracturing or hydrofracturing techniques may be utilized as a preliminary step in the treatment.

With processes according to this invention, it is possible for an operator to treat relatively thick formations as defined hereinbefore and to obtain balanced or selective control of heat front movement and beneficiation through the entire thickness of such formation. This may be done by initiating a combustion front adjacent the bottom of the formation and allowing the gravity difference between injected air or oxygen-enriched gases and the reservoir fluids to exert the characteristic property of causing flame or combustion front propagation upwardly and outwardly from the point of ignition. Alternatively, it is possible to initiate in situ combustion simultaneously at a plurality of levels in the same formation, and by control of the air or oxygen input to plurality of flame or combustion fronts, to obtain a controlled or balanced heating and eduction of variable petroleum constituents from the formation.

When combustion takes place concurrently in both combustion zones, uniform rate of advance is not required, and one advance may be rapid and the other quite slow. Also, it is not necessary to maintain constant temperatures through a given zone, or uniform temperatures in the plurality of zones. Frontal movement is slow when oxygen supply is low and increases as more oxygen is supplied. Thus, control of oxygen input may be regulated to establish any desired condition in the operation.

Various materials may be used in preparing the formation for controlled combustion. When spontaneous ignition is to be utilized various pyrophoric materials may be selected to deposit either as finely divided metals or suitable salts. Examples are either the salts or pure lead, cobalt, iron, nickel and bismuth. Compounds which may be used will include dimethyl zinc, cacodyl and hydrides of phosphorus, boron and silicon. Another type of spontaneous reaction which may be availed of is the reaction of chlorine on finely divided antimony.

Changes and modifications of materials and procedures

may be availed of within the spirit and scope of the invention as defined in the hereunto appended claims.

I claim:

1. A method for controlling combustion in permeable underground carbonaceous deposits, which comprises introducing a combustion catalyst through an injection well into a selected level throughout a permeable portion of such a deposit between said injection well and a production well, directing oxygen-containing gas through said injection well into the portion of said deposit containing the combustion catalyst in a quantity sufficient to initiate zones of spontaneous combustion therein, propagating a combustion front movement from the spontaneous combustion zones by continued introduction of oxygen-containing gas into the selected level of the permeable portion, introducing oxygen-containing gas through a separated passage in said injection well into an adjoining level of the permeable deposit after a predetermined interval for initiating a combustion front movement in said adjoining level substantially simultaneously with the first combustion front movement, and removing evolved products of both frontal movements through the production well.

2. A method for controlling combustion in permeable underground carbonaceous deposits, which comprises introducing a combustion catalyst through an injection well into a selected level throughout a permeable portion of such a deposit between said injection well and a production well, directing oxygen-containing gas through said injection, introducing oxygen-containing gas through a separated combustion catalyst in a quantity sufficient to initiate zones of the permeable deposit after a predetermined period of combustion front movement from the spontaneous combustion zones by continued introduction of oxygen-containing gas into the selected level of the permeable portion, introducing oxygen-containing gas through a separated passage in said injection well into an adjoining overlaying level of the permeable deposit after a predetermined period of combustion front propagation at the selected level for initiating a combustion front movement in said adjoining level substantially simultaneously with the first combustion front movement and at a different rate than in said selected level, and removing evolved products of both frontal movements through the production well.

3. A method for controlling combustion in permeable underground carbonaceous deposits, which comprises introducing a combustion catalyst through an injection well into a selected level throughout a permeable portion of such a deposit between said injection well and a production well, directing oxygen-containing gas through said injection well into the portion of said deposit containing the combustion catalyst in a quantity sufficient to initiate zones of spontaneous combustion therein, propagating a combustion front movement from the spontaneous combustion zones by continued introduction of oxygen-containing gas into the selected level of the permeable portion, introducing oxygen-containing gas through a separated passage in said injection well into an adjoining level of the permeable deposit after a predetermined period of combustion front propagation at the selected level for initiating a combustion front movement in said adjoining level substantially simultaneously with the first combustion front movement, controlling the rate of combustion front propagation at a selected rate in the respective levels by introducing different quantities of simultaneous oxygen-containing gas thereto, and removing evolved products of both frontal movements through the production well.

4. A method for controlling combustion in permeable underground carbonaceous deposits, which comprises introducing a combustion catalyst through an injection well into a selected level throughout a permeable portion of such a deposit between said injection well and a production well, directing oxygen-containing gas through said injection well into the portion of said deposit containing the combustion catalyst in a quantity sufficient to initiate

zones of spontaneous combustion therein, propagating a combustion front movement from the spontaneous combustion zones by continued introduction of oxygen-containing gas into the selected level of the permeable portion, introducing oxygen-containing gas into an adjoining overlaying level of the permeable deposit after a predetermined period of combustion front propagation at the selected level for initiating a combustion front movement in said adjoining level substantially simultaneously with the first combustion front movement, maintaining substantially uniform rate of simultaneous combustion propagation at the respective levels by introducing more oxygen-containing gas into the lower level than is introduced into the upper level, and removing evolved products of both frontal movements through the production well.

5. A method for controlling in situ combustion in relatively thick underground carbonaceous deposits, which comprises penetrating a permeable portion of such a deposit with at least one injection well and at least one production well at horizontally distant locations, disposing a packer in one of said injection wells intermediate the top and bottom of the deposit, introducing a combustion catalyst through said injection well into the permeable portion below the packer level, directing oxygen-containing gas through said injection well into the portion of the deposit containing the combustion catalyst in a quantity sufficient to initiate spontaneous combustion therein, introducing oxygen-containing gas through a separated passage in said injection well into the permeable portion above the packer at a predetermined time interval after initiating combustion in the underlying portion thereof while continuing introduction of oxygen-containing gas into the underlying portion, and removing evolved products of the combustion in both levels through the production well.

6. A method for controlling in situ combustion in relatively thick underground carbonaceous deposits, which comprises penetrating a permeable portion of such a deposit with at least one injection well and at least one production well at horizontally distant locations, disposing a packer in one of said injection wells intermediate the top and bottom of the deposit, distributing an aqueous solution of pyrophoric forming metal throughout the permeable portion below the packer level between the injection well and the production well, next introducing hydrogen sulfide gas into the permeable portion containing the pyrophoric metal, directing oxygen-containing gas into the permeable portion containing the pyrophoric metal and hydrogen sulfide gas in a quantity sufficient to initiate spontaneous combustion in the material previously introduced and establish a frontal advance therein, introducing oxygen-containing gas into the permeable portion above the packer at a predetermined time interval after initiating combustion in the underlying portion thereof, so as to initiate a frontal advance in said upper level, and removing evolved products of the combustion in both levels through the production well.

7. A method for controlling in situ combustion in relatively thick underground carbonaceous deposits, which comprises penetrating a permeable portion of such a deposit with at least one injection well and at least one production well at horizontally distant locations, disposing a packer in one of said injection wells intermediate the top and bottom of the deposit, distributing an aqueous solution of $FeCl_2$ throughout the permeable portion below the packer level between the injection well and the production well, next introducing hydrogen sulfide gas into the permeable portion containing the $FeCl_2$, directing oxygen-containing gas into the permeable portion containing the $FeCl_2$ and hydrogen sulfide in a quantity sufficient to initiate spontaneous combustion in the material previously introduced and establish a frontal advance therein, introducing oxygen-containing gas into the permeable portion above the packer at a predetermined time interval after initiating combustion in the underlying portion

thereof, so as to initiate a frontal advance in said upper level, and removing evolved products of the combustion in both levels through the production well.

8. The method for controlling in situ combustion in relatively thick underground carbonaceous deposits, which comprises penetrating substantially the entire depth of a permeable portion of such a deposit with at least one injection well and at least one production well at horizontally distant locations, disposing a packer in one of said injection wells intermediate the top and bottom of the permeable portion, distributing an aqueous solution of $FeCl_2$ throughout the permeable portion below the packer level between the injection well and the production well, next introducing hydrogen sulfide in natural gas into the permeable portion containing the $FeCl_2$, directing dry air into the permeable portion containing the $FeCl_2$ and hydrogen sulfide in a quantity in a stoichiometric excess of that required to completely react the $FeCl_2$ solution thereby initiating spontaneous combustion and establishing a frontal advance in the permeable portion below the packer level, introducing oxygen-containing gas through a separated passage into the permeable portion above the packer at a predetermined time interval after initiating combustion in the underlying portion so as to initiate and maintain a simultaneous frontal advance in the upper level, and removing evolved products of both frontal movements through the production well.

9. A method for controlling in situ combustion in relatively thick underground carbonaceous deposits, which comprises penetrating a permeable portion of such a deposit with at least one injection well and at least one production well at horizontally distant locations, disposing a packer in one of said injection wells intermediate the top and bottom of the deposit, introducing a combustion catalyst through said injection well and throughout the permeable portion below the packer level, directing oxygen-containing gas through said injection well into the portion of the deposit containing the combustion catalyst in a quantity sufficient to initiate spontaneous combustion therein, introducing oxygen-containing gas through a separated passage into the permeable portion above the packer at a predetermined time interval after initiating combustion in the underlying portion thereof so as to initiate a frontal advance in the upper level substantially simultaneously with the first combustion front movement, and removing evolved products of both frontal movements through the production well.

10. A method for controlling in situ combustion in relatively thick underground carbonaceous deposits, which comprises penetrating a permeable portion of such a deposit with at least one injection well and at least one production well at horizontally distant locations, disposing a packer in one of said injection wells intermediate the top and bottom of the deposit, introducing a combustion catalyst through said injection well and throughout the permeable portion below the packer level, directing oxygen-containing gas through said injection well into the portion of the deposit containing the combustion catalyst in a quantity sufficient to initiate spontaneous combustion therein, introducing oxygen-containing gas through a separated passage into the permeable portion above the packer at a predetermined time interval after initiating combustion in the underlying portion thereof so as to initiate a frontal advance in the upper level substantially simultaneously with the first combustion front movement, determining the combustion front temperatures in the overlaying and underlying portions under treatment, varying the combustion front temperature and rate of advance in each said portion by changing the input of oxygen-containing gas thereto, and removing evolved products of both frontal movements through the production well.
